UNITED STATES PATENT OFFICE.

CHARLES PERNOT, OF RIVE DE GIER, FRANCE.

METALLURGIC AND OTHER FURNACES.

SPECIFICATION forming part of Letters Patent No. 240,037, dated April 12, 1881.

Application filed May 14, 1880. (No model.) Patented in France March 11, 1880.

To all whom it may concern:

Be it known that I, CHARLES PERNOT, a citizen of the Republic of France, and a resident of Rive de Gier, France, have invented 5 certain Improvements in Metallurgic and other Furnaces, (for which I have obtained French Letters Patent March, 1880,) of which the following is a specification.

My invention relates to improvements in the 10 construction of puddling and other metallurgic furnaces, glass-ovens, and furnaces generally which are subjected to very great heat, and hence liable to rapid deterioration; and the object of my invention is so to construct 15 the furnace that its principal parts may be capable of being removed and replaced, so that the furnace can be readily repaired, even when the furnace is in operation.

In the accompanying drawings I have illustrated 20 my invention as applied to one of the well-known Pernot rotary puddling-furnaces, Figure 1, Sheet 1, being a longitudinal vertical section; Fig. 2, Sheet 2, a plan view; Fig. 3, Sheet 3, a transverse section; and Fig. 25 4, an illustration showing the method of suspending the cover of the rotary hearth.

The rotating hearth or receiver A is mounted 30 in an inclined position on a carriage, B, on which it can be freely rotated, a series of rollers, D, mounted in bearings in the hearth being adapted to run on a circular plate, C, on the carriage for that purpose. The carriage B is mounted on wheels running on rails on 35 the floor of the furnace, so that the carriage, with the hearth, can be withdrawn from the furnace, as described in my Letters Patent No. 169,033, October 19, 1875.

Rotary movement is imparted to the hearth 40 from a motor, E, Fig. 2, through suitable gear and shafting carrying a pinion gearing into a circular rack on the under side of the rotary hearth.

F, F', and F'', and F''' are the vertical conduits leading from the regenerators G G', and 45 communicating at their upper ends with corresponding flues or pipes I, I', I'', and I''', which deliver the air and gas into the melting-chamber through openings M in the cover H, supported on brackets J. This cover is 50 provided with a charging-door, N. The vertical gas and air conduits F, F', &c., the

flues I, I', &c., and the cover H, are all composed of fire-bricks or other refractory materials, so bound by metallic bands that the conduits F and F' are in one piece, the conduits F'' and F''' in one piece, the flues I and I' in one piece, the flues I'' and I''' in one piece, and the cover H in one piece, so that any one of these parts can be bodily removed and the same or a corresponding piece be replaced. 55 For this purpose the several parts are provided with hooks K, to which chains L of cranes or other suitable hoisting mechanism may be attached, as indicated by dotted lines in Figs. 1, 2, and 4, the latter figure representing the cover H detached and suspended by the hoisting-chains. In the same way any of the detachable parts of the furnace may be removed for repairs, and this may be done 60 without interfering with the continuous operation of the furnace by having on hand another corresponding part, which may be immediately put in the place of the one removed. 65

Although I have shown the cover H as made 70 in one piece, it may be made in as many parts as may be found desirable.

The conduits F, F', &c., and the flues I, I', &c., may each be made separate.

The principal advantage of this improvement, it will be seen, rests in the quickness 80 with which parts of the furnace may be repaired; whereas in the usual construction of furnaces the repairing of any part necessitates the stoppage of work in the furnace for a considerable length of time. The further advantages are obtained of economy and simplicity 85 in construction; for whereas, in the old form of the Pernot furnace, for instance, the weight of the iron and castings used amounted to thirty-seven thousand kilograms for a furnace capable 90 of melting twenty-five tons, a furnace of the same capacity of the improved construction requires not more than five thousand six hundred kilograms of iron and castings.

The improvements may be applied to other 95 forms of furnaces than that described. For instance, they may be applied to puddling and heating furnaces generally, gas-generator furnaces, blast-furnaces, glass-ovens, &c.

I claim as my invention—

1. The combination of the cover of a furnace, having openings M, with vertical conduits F,

100

F', &c., and the removable flues I I', substantially as described.

2. The combination of the removable cover H, having openings M, with detachable flues I I', and conduits F F', all substantially as specified.

In testimony whereof I have signed my

name to this specification in the presence of two subscribing witnesses.

CHARLES PERNOT.
